UNITED STATES PATENT OFFICE.

ROBERT LEE BENSON, OF CHICAGO, ILLINOIS.

ATOMIZING APPARATUS.

SPECIFICATION forming part of Letters Patent No. 664,923, dated January 1, 1901.

Application filed August 4, 1899. Serial No. 726,178. (No model.)

To all whom it may concern:

Be it known that I, ROBERT LEE BENSON, a citizen of the United States, residing at Chicago, in the county of Cook and State of Illinois, have invented a certain new and useful Improvement in Atomizing Vaporizer Apparatus, (Case No. 1,) of which the following is a full, clear, concise, and exact description, reference being had to the accompanying drawing, forming a part of this specification.

My invention relates to atomizing vaporizer apparatus, which has for its object the provision of an improved apparatus adapted to individual use.

It is well known that the inhalation of vaporized medicaments properly prepared is very efficacious in the treatment of nearly all diseases of the respiratory tract; but one difficulty that has presented itself in the thorough application of drugs to affected air-passages has been in the expense, unsatisfactory action, and imperfect construction of atomizing-inhalers that have been formerly used. Especially is this true of any vaporizing apparatus for individual use that has heretofore been devised. It is also well known that mere inhalation of the medicaments is not sufficient to force them into all portions of diseased lungs from the trachea bronchial tubes down and into the pulmonary alveoli. While it is possible to carry minute nebulized medicaments into the smallest bronchi and pulmonary alveoli of a healthy lung, this is not true of a diseased lung, where it has partially through adhesive inflammation closed these passages, and as scarcely any fresh air enters such lung-passages substances mixed with air will not enter. It is therefore necessary to apply pressure at the entrance of the respiratory passages and by the joint action of pressure and aspiration secure the desired absorption of medicament that the aspiration alone would not effect.

It is the object of my invention to provide inexpensive improved means for overcoming the mechanical difficulties in the way of the satisfactory operation of nebulizing apparatus for individual use by which the chemically-pure atomized vapor may be thoroughly supplied to the air-passages under pressure by the patient himself or by some one for him, either at home or when traveling about.

I will explain my invention in detail by reference to the accompanying drawing, which shows the assembled apparatus partly in section ready for use, the cover of the containing-case being removed.

The essential parts of my apparatus are a pump, a storing-chamber, a nebulizing-chamber, a heater, a filter, and a nebulizer. For portable use I preferably employ a double-acting foot-pump 1 of improved design for furnishing air at practically constant pressure to the storage-chamber 2. I preferably construct the pump of a cylindrical shell 3, 55 having a cover 4 screwed tightly to its upper edge. Two valve mechanisms 5 and 6 at the opposite ends of the pump-shell alternately permit air freely to enter this pump-shell, but effectively prevent its return. I preferably 60 employ a hollow piston-rod 7, with two valve mechanisms 8 and 9. The air of the pump-chamber is freely admitted through these valves into the hollow piston-rod, said valves preventing the return of the air to the pump. 75 The piston consists of the cylindrical portion 10, with its two washers 11 and 12, tightened in place by jam-nuts. In this pump I preferably employ a removable stirrup 13, fastened to the body of the pump by the threaded 80 rod 14. The handle preferably consists of a cross-bar 15, fastened to the fork 16, having threaded engagement with the piston-rod. The air is forced from the piston-rod through 85 a connecting-tube 17, communicating therewith and made preferably of rubber, through a metallic coupling 18 and a metallic tube 19, and through a filter 20 into the storage-chamber 2. This filter consists, essentially, 90 of a cylindrical chamber, into which the inlet and eduction tubes 19 and 21 project a short distance. The filter-chamber is filled with a dust-absorbing material, such as cotton, which thoroughly cleanses the air by riding it of all dust and grit. I preferably allow the inlet and outlet tubes 19 and 21 to project into the filter-chamber in order to have the filtering material securely inclose their ends, so that no unfiltered air can pass the filter by following crevices along the absorbing material. I preferably place some suitable loose gauze saturated with some suitable antiseptic compound, such as oil of cloves, at the bottom of this chamber. I pref- 95 100

erably place enough of the antiseptic compound in the jar 2, so that a little free oil or compound will be present. The oil-vapor mixes with the air and renders it antiseptic.

5 The antiseptic air leaves the storing-chamber by means of the tube 22, which leads it through the vaporizer or nebulizer 23 into the nebulizing-chamber 24. This nebulizer is of an improved construction which is especially 10 valuable in this apparatus. Nebulizers as previously constructed required great skill in their manufacture and were of such nature that their parts became easily displaced and destroyed, and it was extremely difficult 15 to properly clean them. In the nebulizer of my construction I preferably employ a metal tube 25, which is closed at its lower end. I preferably construct the tube with an increased outer diameter a short distance from 20 the bottom, thereby forming a projection 26, which enables it to fit snugly against another tube 27, which is slipped over its lower part. A smaller tube 28, whose upper surface is 25 preferably made slanting and which is tapered slightly at the top, is fastened to the tube 27. This is a satisfactory arrangement of uniting the tubes 25 and 28, although means other than those employed may be used. The tube 28 dips into the medicated 30 menstruum 29. A duct 30 leads from the tube 25 through the enlarged portion 26 into the chamber 24. This preferably slanting duct is preferably placed in such manner as to just fail to clear the slanted and tapered 35 top of tube 28. When the air passes through this duct, it draws the liquid 29 through the tube 28 by means of its suction. The medicated menstruum upon coming in contact with the air under pressure is vaporized and 40 blown in a fine spray toward the upper part of the nebulizing-chamber against its side, the excess returning to the bottom of the chamber.

45 The vaporized medicament is conducted by means of a tube 31 from the nebulizing-chamber to a heater 32, which consists, preferably, of coiled metal tubing through which the atomized vapor circulates. This tubing is inclosed by an asbestos or sheet-metal box 33 or may be left exposed, according to the degree 50 of heat desired. Heat is supplied to the surrounding and inclosed air-space by a small lamp 34, preferably placed below the heater. Small openings may be provided in the heater 55 cap or casing to promote circulation. The heat generated raises the temperature of the vaporized medicament some degrees higher than the normal temperature of the throat or lungs in order to facilitate the deposition of 60 the vaporized medicament upon the colder pulmonary passages, thus promoting and assisting the penetrability of the vaporized medicament. Absorption is also aided by the heat, which is quite as important, whereby 65 consolidated areas inclosing encapsulated bacilli may be reached. The heater may be used to heat the air passing into the nebulizer

instead of heating the vapor leaving it with equally-good results, according to the effect of heat on the medicaments used. A drip 35, 70 preferably consisting of a tube 36, with a screw-cap 37, is also preferably provided for the purpose of drawing off any condensed liquid. From the heater the vaporized medicament is conducted to the affected lung-passages by means of a tube 38, which is preferably of large diameter and is preferably constructed of rubber, terminating in a nozzle provided for insertion within the nose or mouth, or an inhalation face-mask may be used, covering both the nose and mouth. 80

I preferably employ a coupling 39 between the heater and the rubber, which will not conduct heat rapidly. I preferably provide a by-pass 40 between the inlet-tube 22 of the 85 nebulizing-chamber and its outlet-tube 31. I preferably employ a stop-cock 41 in this by-pass, which is closed when the apparatus is used as an ordinary nebulizing-inhaler. I also preferably employ a stop-cock 42 in the 90 outlet-tube 31, which in the ordinary operation is open. To utilize the apparatus for washing or spraying the affected passages or to secure hot air alone, I preferably close the stop-cock 42 and open the stop-cock 41, and the filtered antiseptic air may pass directly 95 through the heater to a wash-bottle or other apparatus without passing through the nebulizing-chamber. All parts and connections or connecting-tubes are preferably made of some material that is not attacked by the medicaments used—as, for instance, glass or block-tin—the kind of material used being determined by the nature of the medicaments employed. 100

105 By the application of antisepticized air under pressure to the apparatus I am enabled to supply the germicide medicament to all affected passages without depending solely on the endosmotic power of the lungs. The pulmonary areas with impaired respiratory capacity are reached by means of this pressure, and any germ will be medicinally acted upon unless it be too thickly encapsulated; in which case, however, it is unlikely to do further 110 damage.

115 The piston working back and forth in the cylinder of the pump also generates heat by its frictional contact with the interior of the cylinder, so that the air is heated before it is 120 passed into the hollow piston-rod.

125 While I have herein shown and particularly described the preferred embodiment of my invention, I do not wish to be limited to the precise construction or arrangement shown, as changes in the details of the apparatus may readily be made without departing from the spirit thereof; but,

Having thus described my invention, I claim as new, and desire to secure by Letters 130 Patent, the following:

1. In an atomizing apparatus, the combination with a pump, of a filter through which the pump is adapted to force air under pres-

sure, a chamber 2 for receiving the air, a tube 22, a chamber 24, a tube 25 within the latter chamber and having communication with a tube 22, a nebulizer communicating with the tube 25, a coiled metallic tube 32, means for heating said tube, a rubber or composite tube 38 communicating with the tube 32, and a non - heat - conducting coupling uniting the tube 38 with the tube 32, substantially as described.

2. In an atomizing apparatus, the combination with a pump provided with a tube 17 for conveying air under pressure, an air-chamber 2 for containing antiseptic communicating with said tube, a filter 20 through which air is passed into the chamber, a second tube 22, a third tube 25 communicating with the tube 22, a second chamber 24 for containing medicament, a duct 31, and a nozzle in communication with said duct, substantially as described.

3. In an atomizing apparatus, the combination with a pump provided with a tube 17 for conveying air under pressure, an air-chamber 2 for containing antiseptic communicating with said tube, a filter 20 through which air is passed into the chamber, a second tube 22, a third tube 25 communicating with the tube 22, a second chamber 24 for containing medicament, nebulizing means communicating with the tube 25 and located within the chamber 24, a duct 31, and a nozzle in communication with said duct, substantially as described.

4. In an atomizing apparatus, the combination with a pump provided with a tube 17 for conveying air under pressure, an air-chamber 2 for containing antiseptic communicating with said tube, a filter 20 through which air is passed into the chamber, a second tube 22, a third tube 25 communicating with the tube 22, a second chamber 24 for containing medicament, nebulizing means communicating with the tube 25 and located within the chamber 24, a duct 31, a nozzle in communication with said duct, and means for heating the vapor, substantially as described.

5. In an atomizing apparatus, the combination with an air-chamber 2, of a duct leading thereto, a pump for supplying air through said duct, a filter through which the air is passed, a second chamber for containing medicament having communication with the aforesaid chamber, a duct leading from the second chamber, a by-pass, and means associated therewith for cutting out one of the said chambers, substantially as described.

6. In a portable atomizing apparatus, the combination with a chamber for containing material to be vaporized, of a pump communicating with said chamber, a filter through which air is passed from the pump to the chamber, a duct leading from the chamber, and a nozzle having communication with said duct, substantially as described.

7. In a portable atomizing apparatus, the combination with a chamber for containing material to be vaporized, of a double-acting pump communicating with said chamber, a filter through which air is passed from the pump to the chamber, a duct leading from the chamber, and a nozzle having communication with said duct, substantially as described.

8. In a portable atomizing apparatus, the combination with a chamber for containing material to be vaporized, of a pump communicating with said chamber, a filter through which air is passed from the pump to the chamber, a duct leading from the chamber, a nozzle having communication with said duct, means for heating the medicated air, a tube to which the air is conveyed after being heated, and a coupling formed of a non-heat-conducting material for conveying the air after being heated to the tube, substantially as described.

In witness whereof I hereunto subscribe my name this 2d day of August, A. D. 1899.

ROBERT LEE BENSON.
